UNITED STATES PATENT OFFICE.

WILLIAM JOHNSTON, OF MENOMINEE, MICHIGAN.

SPRING-VEHICLE.

SPECIFICATION forming part of Letters Patent No. 351,775, dated November 2, 1886.

Application filed June 29, 1886. Serial No. 206,630. (No model.)

To all whom it may concern:

Be it known that I, WILLIAM JOHNSTON, a citizen of the United States, residing at Menominee, in the county of Menominee and State 5 of Michigan, have invented a new and useful Improvement in Spring-Vehicles, of which the following is a specification.

My invention relates to spring-vehicles; and it has for its object to equalize the effect of the 10 load upon the springs, so that the vehicle-body shall remain at all times parallel with the axles and running-gear.

My invention consists in a guide-bar suitably mounted upon the running gear and working through the body, as hereinafter described and claimed.

In order that my invention may be fully understood, I will proceed to describe it with reference to the accompanying drawings, in 20 which

Figure 1 is a side elevation of a buggy with my improvements applied, the nearside of the vehicle-body being partially broken away to more clearly expose the parts. Fig. 2 is a plan view. Fig. 3 is a perspective view of a modified form of my invention applied to a spring-vehicle, the body of the latter being shown in skeleton form. Fig. 4 is a detached longitudinal section on the line $x-x$, Fig. 2. Fig. 5 is a 30 detached transverse section on the line $y-y$, Fig. 2.

Vehicles of all kinds, particularly light passenger vehicles—such as buggies, &c.—are defective in construction, because, if there be a 35 heavier load on one side than on the other, the spring or springs which directly sustain the heavier load will be much more compressed than the other springs, and hence the body of the vehicle will be tilted sidewise, causing the 40 occupants much discomfort and greatly straining the vehicle. By virtue of my invention the vehicle-body always remains level with the axles and running-gear, notwithstanding unequal distribution of the load.

45 In the accompanying drawings, A designates the vehicle-body; B B, the springs, and C, the running-gear. As illustrated, the springs are of the arc type, and are arranged one beneath each side of the body and extending longitudinally of the body. The axles D D are 50 connected together by three longitudinal bars,

E, and the springs are clipped to the front and hind axles outside of the outer bars, E.

Upon the bottom of the vehicle-body, in Fig. 1, is a shaft, F, extending transversely of the 55 body and embraced at its ends by straps g. Upon the extremities of this shaft is mounted a gear-pinion, f.

H designates a rack-bar, which is secured to the outer sides of the two outside bars E by a rod, 60 E', extending transversely of the frame. Each rack-bar H extends upward through apertures in the bottom on one side of the pinions f, so that the teeth of said pinions mesh with the teeth on the side of the rack-bar. 65

In Fig. 2 a slight modification is shown, there being two shafts, F, with two pinions, f, on each side of the buggy-bottom, and the racks H being double, having teeth on both sides, and located in the space between the pinions of each 70 pair, so as to engage with both pinions. In either form of construction the operation is the same. Even if all the load be on one side of the vehicle-body, it will not be tilted, because any depression of one side of the vehicle- 75 body must be equally shared by the other side.

The invention is equally applicable to heavy as well as light vehicles, and to other than passenger-vehicles. The form of springs and running-gear, as well as the number of axles, is 80 immaterial to the invention, because the rack-bars may be applied directly to the axles, or otherwise, without departing from the spirit of the invention.

I do not wish to be limited to the use of rack-bars, as plain guide-bars may be employed secured in the same manner as the rack-bars, and work through the body between suitably-arranged friction-rollers. However, I consider rack-bars much the preferable form in which 85 to embody the invention in practice.

By reference to Fig. 5 it will be seen that the blocks on the under side of the body to which the springs are bolted serve to hold the rack-bars from outward or lateral movement. 95

Having thus described my invention, I claim—

1. In a vehicle, the combination, with the running-gear, a body, and the springs intermediate of the body and gear, of the vertically-disposed guide-bars arranged on opposite sides of the body and passing through the same, sub-

stantially as described, for the purpose set forth.

2. In a vehicle, the combination, with a body, the running-gear, and the intermediate springs, of the vertically-disposed guide-bars connected to the running-gear and passing through the body on opposite sides thereof, and the wheels in contact with the sides of the said guide-rods, substantially as described, for the purpose set forth.

3. In a vehicle, the combination, with a body, the running-gear, and the intermediate cushion-springs, of the vertically-disposed guide-rods carried by the running-gear and passing through the body within the vertical sides of the same, and the wheels arranged within the body and in contact with the sides of the same, substantially as described.

4. In a vehicle, the combination, with the running-gear, a body, and the intermediate springs, of the vertical guide-bars having the racks, and connected to the running-gear, and passing through the body on opposite sides thereof, and the toothed or gear wheels, which mesh with the racks on the said bars, substantially as described.

5. In a vehicle, the combination, with a body, the running-gear thereof, and the intermediate springs, of the vertical guide-bars having the racks, and pivotally connected to the running-gear, and passing through the body, and a shaft journaled on the body and carrying the

toothed wheels which mesh with the racks on the guide-bars, whereby when the body descends under the weight of its load the guide-bars will rotate the shafts and its wheels to maintain the body in a horizontal position, substantially as described.

6. The combination, with the body, springs, and running-gear of a vehicle, of a shaft carrying rigid pinions and secured to the vehicle-body, and a corresponding number of racks secured to the running-gear, substantially as set forth.

7. The combination, with the body, springs, and running-gear of a vehicle, of the rack-bars H, shaft F, and pinions f, substantially as described.

8. The combination, with the running-gear and body of a vehicle, of guide-bars mounted in the running-gear and working through the body, as set forth.

9. The combination, with the two shafts F, having two pinions, f, on each side of the wagon-bottom, of the rack-bar H, having teeth on each side and engaging with both rack-bars, as set forth.

In testimony that I claim the foregoing as my own I have hereto affixed my signature in presence of two witnesses.

WILLIAM JOHNSTON.
